UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,948, dated June 24, 1890.

Application filed April 15, 1890. Serial No. 348,122. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

Referring to the drawing, A is the body of the handle. B is the head, and C is the base portion thereof. The body part A tapers from the base part C to the head part B, with a gradual increase in diameter, and consists of alternate bands D and E, arranged like spirals or helices alternately one above the other. The part D is plain and slightly concave, and the part E is highly ornamented to indicate a feather. The head B has the top portion F plain and formed like a cap, and convex portion J of shaded or ornamental work, which is relieved by the depending and up-

wardly-extending ornamented portions G and I. The head B is separated from the body part A by a rib or band H. The base part C is formed with the upper and lower bands K, the enlarged or convex portion L, which is ornamented to correspond with the part J, and the ornamental figures M N, corresponding substantially to the figures G I.

The handle may be made of any suitable material.

Having now described my new design, what I claim as new, and desire to secure by Letters Patent, is—

The design for umbrella or cane handles, substantially as herein described and shown.

In testimony of which invention I have hereunto set my hand.

HENRY O. SCHMIDT.
